Primary Examiner — Elizabeth J Oswecki(74) *Attorney, Agent, or Firm* — Daniel J. Schlue; Roetzel & Andress(57) **CLAIM**

The ornamental design for a faceguard, as shown and described.

DESCRIPTION

FIG. 1 is a perspective view of a faceguard showing our new design;

FIG. 2 is a front view of the faceguard;

FIG. 3 is a rear view of the faceguard;

FIG. 4 is a side view of the faceguard, the opposite side view being a mirror image of this side view;

FIG. 5 is a top view of the faceguard; and,

FIG. 6 is a bottom view of the faceguard.

In the drawings, the broken lines in FIG. 1 depict portions of the design that form no part of the claim.
